[57] CLAIM

The ornamental design for a guide for cutting and sawing pipe insulation, substantially as shown and described.

DESCRIPTION

FIG. 1 is a top-front perspective view of a guide for cutting and sawing pipe insulation showing my new design;

FIG. 2 is a bottom plan view of FIG. 1 on a reduced scale;

FIG. 3 is a rear elevational view of FIG. 1 on a reduced scale.

FIG. 1

FIG. 2

FIG. 3
